FIG. 1

FIG. 2

Andrew H. Neureuther INVENTOR.

UNITED STATES PATENT OFFICE

1,977,350

ELECTRIC CLOCK

Andrew H. Neureuther, Peru, Ill., assignor to
 Western Clock Company, Peru, Ill., a corpora-
 tion of Illinois

Application December 1, 1930, Serial No. 499,276

15 Claims. (Cl. 53—26)

My invention relates to clocks driven by self-starting synchronous motors that are driven by the alternating current of commercial power and lighting lines and has for its object the production of a simple means associated with the self-starting synchronous motor that drives the clock hands to show or visually indicate that there has been a current interruption in the power supplying line for a sufficient period of time to cause the motor to stop and thus to thus caution an observer that, although the clock is again actuating the time indicated by the clock hands is not absolutely accurate so that the hands can be reset again to the correct time.

A further object of the invention is to produce a means associated with the above whereby the actual resetting of the hands of the clock to the correct time will simultaneously reset the showing or indicating means so that it will again be in position to indicate another current interruption.

I accomplish the above results by the means shown in the accompanying drawing in which:

Fig. 1 is a sectional view showing my invention with the driving motor and indicating means in normal operative position before a current interruption has taken place.

Fig. 2 is a similar sectional view showing my invention with the driving motor stopped and the indicating means showing that the current has been interrupted.

Similar numerals indicate the same parts through the several views.

In the drawing 1 represents a self-starting synchronous motor the same as the type shown and described in my previous application Serial No. 463,145 filed June 23, 1930, now Patent No. 1,962,832 of June 12, 1934 so that it will not be necessary to further describe it herein. 2 is the armature shaft which has the endwise motion and is connected to the clock hands 4 and 5 by means of an elongated gear 6 mounted on said shaft in connection with the usual train of gears for the purpose diagrammatically indicated and shown in the drawing associated with plates 10, 11 and 12. Shaft 2 is mounted in the bearing plates 29 which are fastened on each side of the field core 30, as shown. Mounted on said shaft 2 within the influence of the pole pieces 31 of said field core 30 is the rotor 32 which is cup shaped, as shown, and which has a toothed or serrated edge having the teeth or serrations 33 whose forward parts are narrower than the rearward parts thereof where said teeth join or form a part of the rim of the cup shaped member 32, as

shown. Mounted on shaft 2 is a disc 34 which operates in the slot shown in member 35 which member is pivotally connected to a frame 36 fastened on 29 by means of the pin 37, as shown. Said member 35 has a projecting part 38 which carries a member 39 of magnetic material or a magnetized member having one or more salient poles such as is shown at 40. Said parts 40, 39 and 38 are counter-weighted by means of the weight 41 mounted on arm 42 which is fastened to the member 38. The parts 39 and 40 comprise a member which co-acting with the teeth 33 on rotor 32 (the outer surface of said rotor 32 has a substantial amount of remanence to cause it to rotate in a rotating magnetic field such as is used in self-starting induction motors at a substantially high rate of rotation especially when the parts 39 and 40 are in the position shown in Fig. 2) when in the position shown in Fig. 1 cause the rotor to run at synchronous speed so that I have designated this as a synchronizing element in the above mentioned application Serial No. 463,145. It is evident from the description that follows that when there has been a current interruption that this synchronizing element will be in the position shown in Fig. 2 so that when the current comes on the circuit again the rotor will start to rotate and shift sidewise in the magnetic field until the synchronizing element is brought adjacent to the teeth or salient points on the rotor which will thus influence and cause the rotor to run at synchronous speed. Adjacent to said hands is the usual clock dial 7 which has an additional aperture 8 as shown. Mounted adjacent to said aperture 8 and pivotally mounted in plate 10 by means of the bracket 13 and pin 14 is a lever 15 which has a tail 16 projecting below the pivot pin 14 and two angular faces 17 and 18 formed on the part of said lever 15 above said pin 14. In order to distinguish the faces from each other the face 18 may be of a color different, say red, from that of the face 17 which it may be preferable to leave the same color as the face of the dial 7. In the forward position of the lever 15 shown in the solid lines in Figure 2 it is evident that the red color of face 17 will show very conspicuously through the aperture 8 in the dial 7, and the face 17 in the backward position of the lever 15, shown in the dotted lines in said Figure 2 or in the position shown (in the solid lines) in Figure 1 will hardly be evident to an observer. The lever 15 is so constructed that the center of gravity is to the right of the pivot 14 in the position of said lever shown in Figure 1 (and in the dotted position indicated in Figure 2) 110

so that it will remain against the plate 10, and further is such that when the lever 15 is in the position shown in the solid lines in Figure 2 the center of gravity will be to the left of the pivot 5 14 and it is evident will remain in either one position or the other shown until moved sufficiently to pass the center of gravity vertically over the center of the pin 14.

From the description the motor described in 10 the previous specification it is evident that when the current is on the power line and it passes through the field winding of the motor that the armature with its shaft 2 is pulled into the magnetic field in the position shown in Figure 1 when 15 the lever 15 can be placed in the position shown in said Figure 1 by means to be described below. As soon as the current is interrupted it is evident that the armature 2 will be pushed forwardly by means of the spring 19 in the bearing of my 20 motor so that the end will strike the upper part of the said lever 15 and throw it forwardly against the dial and aperture as shown in Figure 2 permitting the color (red) of the face 18 to show conspicuously through the aperture 8 in dial 7. 25 It is evident, since there is no connecting link between the shaft 2 and the lever 15, that said lever 15 will remain in said position even if the current starts to flow again and pulls the armature shaft 2 back into the starting magnetic field 30 of my motor.

Connected with the hands is a gear 20 which can be made to engage with a gear 21 which is mounted on a shaft 22 which is slidably mounted in the plate 12 as shown and has a knurled finger piece 23 and holds the gears 20 and 21 out of mesh by means of the spring 24 between the finger piece 23 and the plate 12, said shaft 22 being maintained in its inoperative position by means of the collar 25 on said shaft 22. It is evident that 40 the hands 4 and 5 (which are for convenience shown diagrammatically connected with the self-starting synchronous motor) can be properly actuated by the motor and be set by means of the finger piece 23 in the manner that is familiar in the art. In my invention I utilize the sidewise 45 axial motion of the finger piece 23 in setting the hands to correct time to simultaneously set the lever 15 from its position in the solid lines in Figure 2 to its position shown in Figure 1, by means 50 of a member 26 slidably mounted in the plates 10 and 11. Member 26 on its right hand end has two projections 27 which loosely embrace the gear 21 and it is evident therefrom that any sidewise 55 axial motion of said gear 21 is directly communicated to said member 26. On the left hand end of said member 26 adjacent to the lower projection or tail 16 of the lever 15 are two projections 28 so sufficiently spaced as to form a lost motion 60 connection between said member 26 and the tail 16 of said lever 15, so that when the finger piece 23 is pushed in so that the gear 21 will be in engagement with the gear 20 and projections 28 will be in dotted positions shown in Figure 2, the lever 15 will be moved from the position shown 65 in solid lines in Figure 2 to the position shown in Figure 1, in which position the lost motion connection above mentioned will permit the member 26 to return to its normal position shown in the solid lines in both Figures 1 and 2.

70 It will be understood, of course, that while I have shown one form of my invention I do not wish to limit myself to the exact form shown, but desire to have it taken as illustrative of the many forms that come fairly within the scope of 75 the appended claims.

I claim:

1. In an electric clock, means for producing a rotating magnetic field from a commercial alternating current lighting system, a shaft slidably and rotatively mounted in said field, a rotor mounted on said shaft substantially disposed within said field when said current flows, resilient means co-acting with said shaft to remove the rotor from said position in said field when said current stops flowing, in combination with time indicating means driven by said shaft, a dial having an aperture and a member including signalling means actuated by said shaft upon the interruption of said current to position said signalling means in registration with said aperture. 80

2. In an electric clock, means for producing a rotating magnetic field from a commercial alternating current lighting system, a shaft slidably and rotatively mounted in said field, a rotor mounted on said shaft substantially disposed within said field when said current flows, resilient means co-acting with said shaft to remove the rotor from said position in said field when said current stops flowing, in combination with time 85 indicating means driven by said shaft, a dial having an aperture, a member including signalling means actuated by said shaft upon the interruption of said current to position said signalling means in registration with said aperture. 90

3. In an electric clock, means for producing a rotating magnetic field from a commercial alternating current lighting system, a shaft slidably and rotatively mounted in said field, a rotor mounted on said shaft substantially disposed within said field when said current flows, resilient means co-acting with said shaft to remove the rotor from said position in said field when said current stops flowing, in combination with time indicating means driven by said shaft, a dial having an aperture, a member including signalling means actuated by said shaft upon the interruption of said current to position said signalling means in registration with said aperture, and manual means for resetting said member. 100

4. In an electric clock, means for producing a rotating magnetic field from a commercial alternating current lighting system, a shaft slidably and rotatively mounted in said field, a rotor mounted on said shaft substantially disposed within said field when said current flows, resilient means co-acting with said shaft to remove the rotor from said position in said field when said current stops flowing, in combination with time indicating means driven by said shaft, a dial having an aperture, a member including signalling means actuated by said shaft upon the interruption of said current to position said signalling means in registration with said aperture, and manual means for resetting said member and said 110 time indicating means. 115

5. In an electric clock, means for producing a rotating magnetic field from a commercial alternating current lighting system, a shaft slidably and rotatively mounted in said field, a rotor mounted on said shaft substantially disposed within said field when said current flows, resilient means co-acting with said shaft to remove the rotor from said position in said field when said current stops flowing, in combination with time indicating means driven by said shaft, a dial having an aperture and a signalling means visible through said aperture actuated by said shaft upon the interruption of said current to position said signalling means in registration with said 125 aperture. 130

6. In an electric clock, means for producing a rotating magnetic field from a commercial alternating current lighting system, a shaft slidably and rotatively mounted in said field, a rotor mounted on said shaft substantially disposed within said field when said current flows, resilient means co-acting with said shaft to remove the rotor from said position in said field when said current stops flowing, in combination with time indicating means driven by said shaft, a dial having an aperture, a signalling means visible through said aperture actuated by said shaft upon the interruption of said current to position said signalling means in registration with said 140 145 aperture. 150
